[57] **CLAIM**

I claim the ornamental design for a hand tool for cutting and stripping wire and cable, shown and described.

DESCRIPTION

FIG. 1 is a front view of a hand tool for cutting and stripping wire and cable showing my new design;

FIG. 2 is a rear view thereof;

FIG. 3 is a top plan view;

FIG. 4 is an underside plan view thereof;

FIG. 5 is a view of one end thereof;

FIG. 6 is a view of the opposite end thereof;

FIG. 7 is a front view with a top movable part in alternative position; and,

FIG. 8 is a front view with a further part in alternative position.
